CLAIM

The ornamental design for a combined message holder and signal, substantially as shown and described.

DESCRIPTION

FIG. 1 is a top plan view of a combined message holder and signal showing my new design;

FIG. 2 is a front elevational view thereof;

FIG. 3 is a rear elevational view thereof;

FIG. 4 is a bottom plan view thereof;

FIG. 5 is a right end elevational view, the left end being a mirror image thereof.
